TELEPHONE SIGNALING SYSTEM

Elliot M. Staples, Hohokus, N. J., assignor to
American Telephone and Telegraph Company,
a corporation of New York

Application June 21, 1932, Serial No. 618,519

9 Claims. (Cl. 179—170)

This invention relates to telephone systems and more particularly to improvements in signaling arrangements associated with the lines of such systems.

5 The signaling arrangements of the invention are adapted for toll circuits in a telephone system when these circuits are equipped with devices for the suppression of echoes. When used with such circuits, they permit signals to be 10 transmitted in both directions on the circuit simultaneously, thereby permitting any given operator, for example, the operator originating the call, to completely supervise the call. Recall or disconnect signals could be transmitted 15 by the originating operator and received at the distant end at the same time that switchhook signals, audible ringing tone, busy signals, voice currents or other tones are being transmitted over the circuit in the opposite direction. The 20 arrangements of the invention differ from other signaling systems in that they permit the signals to be passed in the two directions simultaneously over circuits which would otherwise be cut one way by the operation of an echo suppressor.

25 As is well known in the art, echo suppressors are added to telephone circuits in order to prevent voice currents from being transmitted over the circuit in the two directions simultaneously. 30 If this were not done, some of the current, reflected back due to an irregularity, would enter the talker's telephone, and if it was of sufficient magnitude and was delayed sufficiently by the circuit, he would hear an echo of his own voice. 35 Also, some of this delayed current would be reflected again and be transmitted to the listener's telephone and, if severe, would cause the listener to hear an echo following the direct transmission. For a full and complete discussion and 40 illustration of echo suppressors, reference is made to an article by A. B. Clark and R. C. Mathes in the Journal of the American Institute of Electrical Engineers, June 1925, pages 618 to 626.

45 In a signaling system, it is possible by means well known in the art to design the system so that echo currents do not interfere with its operation. Therefore, it is possible to disable the echo suppressors while signaling. This is accomplished by the arrangements of the invention, which consist in providing receiving ringers at the echo suppressor points. These receiving ringers are arranged to be operated by certain signals but not by the voice currents on other tones in a manner well known in the art.

These ringers would be connected to the lines and to the echo suppressor circuits in such a manner that the operation of these ringers would remove the short circuit or open circuit applied to the line by the operation of the echo suppressor or prevent the short circuit or open circuit from being applied, thereby allowing the signal to be passed to the distant end of the circuit. Further details of the system may be more fully understood from the detailed description thereof hereinafter given.

5 The invention may be more fully understood from the following description together with the accompanying drawing in Figures 1, 2 and 3 of which the invention is illustrated. Fig. 1 shows 15 a telephone circuit embodying the signaling arrangements at the terminals as well as those of the invention. Figs. 2 and 3 show some alternative arrangements at the echo suppressor point of connecting the signaling apparatus to the circuit and echo suppressors.

20 In Fig. 1 of the drawing is shown a telephone circuit L connecting points A and B, together with enough of the operator's cord circuits, 13 and 18, to illustrate the operation of the signaling system. The line L is of the well-known four-wire type comprising two one-way line sections, 1 and 2, for transmission in opposite directions, and might include the one-way amplifiers A₁, A₂, A₃, A₄, A₅ and A₆. These lines would be connected 25 to the line jacks, 19 and 20, through the hybrid coils 3 and 4 and networks N₁ and N₂, respectively, in a manner well known in the art. Connected to the two-wire portion of the circuit at point 21 would be sending ringer 5 and receiving 30 ringer 6, and connected to the circuit at point 22 would be sending ringer 7 and receiving ringer 8. These ringers are of the well-known type, the sending ringers being arranged so that different frequencies are transmitted in the two 35 directions over the circuit, and the receiving ringers are arranged to be operated by the frequency received from the distant end of the circuit and not by the local frequency. In the drawing, the sending ringer 5 is arranged to send 40 out 1400 cycles and the receiving ringer 8 to receive this frequency. Sending ringer 7 is arranged to send out 1000 cycles and receiving ringer 6 to receive this frequency. At points 23 and 24 of the circuit is connected echo suppressor 9. 45 This echo suppressor is of the well-known type comprising two amplifier detectors with relay systems arranged to short-circuit line 2 when voice or other currents are being transmitted over line 1, and to short-circuit line 1 when 50

55

transmission is over line 2. At points 25 and 26 of the circuit are connected receiving ringers 10 and 11. These ringers are of the well-known type and are arranged to operate on both 1000 and 1400-cycle currents, but not on voice currents or other tones. The operation of these ringers at the echo suppressor point causes the short circuit, connected to the line by the echo suppressor, to be removed or prevents the short circuit from being applied.

With the signaling system shown on Fig. 1, when cord circuit 13 is connected to line jack 19 and relay 33 of sending ringer 5 is operated by closing ringing key 14, a 1400-cycle signal is applied to line 1. This causes receiving ringer 10 connected to the line at point 25 to operate, which causes relay 27 to operate. The operation of this relay disconnects echo suppressor 9 from point 23 of the circuit. It also causes receiving ringer 8 connected to the line at point 22 to operate, which causes relay 36 to operate. The operation of this relay causes the line lamp 31 to light. If at this time cord circuit 18 is connected to line jack 20 and relay 35 of sending ringer 7 is operated by closing ringing key 30, a 1000-cycle signal is applied to line 2. This causes receiving ringer 11 connected to the line at point 26 to operate, which causes relay 28 to operate. The operation of this relay disconnects echo suppressor 9 from point 24 of the circuit. It also causes receiving ringer 6 connected to the line at point 21 to operate, which operates relay 34. This causes cord lamp 16 to light.

Accordingly, it is seen that, by the arrangements of this invention, the signals may be transmitted over lines 1 and 2 simultaneously, which would otherwise be impossible, as the signal from A to B over line 1 would cause relay 29 of echo suppressor 9 to operate, which would short-circuit line 2 at point 24, thereby blocking the transmission of the signal from B to A. Similarly, a signal sent from B to A would cause echo suppressor 9 to operate which would operate relay 38. This would short-circuit line 1 at point 23, thereby blocking transmission of the signal from A to B. If voice currents are being transmitted from A to B or from B to A, receiving ringers 10 and 11 do not operate and the echo suppressor operates in the regular manner to short-circuit line 2 if transmission is from A to B, and line 1 if transmission is from B to A.

When voice currents or tones other than the signal are being transmitted from A to B over line 1, relay 29 of echo suppressor 9 operates to short-circuit line 2 at point 24. If at this time relay 35 of sending ringer 7 is operated by closing ringing key 30, the 1000-cycle signal is applied to line 2. As receiving ringer 11 is connected to the line in such a manner that the short circuit applied to the line by relay 29 does not affect the voltage applied to this ringer, relay 28 will be operated to remove the short circuit applied to the line at point 24. This allows the signal to be passed in the same manner as described above. It also prevents relay 30 of echo suppressor 9 from short-circuiting line 1. The arrangements of the invention would operate equally as well if voice currents were being transmitted from B to A at the same time that a signal is passed from A to B.

In Fig. 2 is shown a modification of the arrangements at the echo suppressor point of Fig. 1. Similar reference characters have been utilized to denote like parts in both arrangements. The two arrangements differ in that in Fig. 2 one receiving

ringer is used at the echo suppressor point in place of the two ringers of Fig. 1. The same results are obtained by the arrangements of Fig. 2 as of Fig. 1, by switching the receiving ringer, by means of relays connected to the echo suppressor, to the points in the circuit where it is required. In the arrangements shown by Fig. 2 the echo suppressor 9 is connected to lines 1 and 2 in the same manner as in Fig. 1. To the half of the echo suppressor connected to point 23 are connected the windings of relays 40 and 41 in such a manner that the operation of this part of the echo suppressor will cause these relays to operate. With relays 40 and 41 operated, the input of the receiving ringer 10 is connected to point 26 of line 2, and the winding of relay 28 is connected to the output of the ringer. With relays 40 and 41 not operated, the input of ringer 10 is connected to point 25 of line 1, and the winding of relay 27 is connected to the output of the ringer.

When a signal is passed from A to B over line 1, ringer 10 may operate before the echo suppressor operates, in which case relay 27 is operated, which prevents the echo suppressor from short-circuiting line 2 at point 24, and a signal may be passed from B to A over line 2. If, when the signal is being passed from A to B over line 1, the echo suppressor operates before ringer 10, line 2 is short-circuited at point 24 and relays 40 and 41 operate. If at this time a signal is passed from B to A over line 2, the ringer connected to point 26 operates, which operates relay 28. This removes the short circuit and allows the signal to be passed. This arrangement operates equally as well when a signal is passed from B to A before a signal is passed from A to B, or when a signal is passed in either direction when voice currents or other tones are being passed in the opposite direction.

In Fig. 3 is shown a modification of Fig. 2. Similar reference characters have been used to denote like parts in both arrangements. The arrangement of Fig. 3 differs from that of Fig. 2 in that the receiving ringer at the echo suppressor point is permanently connected to one of the lines. When voice currents, signals or other tones are passed from A to B over circuit 1, the echo suppressor operates to short-circuit line 2. A signal sent from B to A will operate ringer 10, and relay 28 will remove the short circuit and the signal will be passed. A signal sent from B to A will prevent the echo suppressor from short-circuiting line 1 and a signal may be passed from A to B at the same time. This arrangement differs from the arrangements of Figs. 1 and 2 in that when voice current or tones other than the signals are being transmitted from B to A over line 2, the echo suppressor will short-circuit line 1 and signals cannot be passed from A to B while these voice currents or tones are being applied.

In this description the sending and receiving ringers at the terminals are shown connected to the two wire portion of the circuit. This signaling system will operate equally as well if these ringers are connected to the four-wire portion of the circuit. This could be done by connecting sending ringers 5 and 7 to the lines at the inputs to amplifiers A₁ and A₆, respectively, and receiving ringers 6 and 8 to the lines at the outputs to the amplifiers A₂ and A₅, respectively. Also, the echo suppressor and receiving ringers at this point are shown connected to the four-wire portion of the circuit. This system would operate equally as well on a two-wire circuit.

Obviously, frequencies or combination of fre-

quencies other than 1000 or 1400 cycles could be used in the signaling arrangements of the invention. These frequencies have been referred to as desirable for purposes of illustration. Also, the 5 relay contact operated by the receiving ringer at the echo suppressor point is shown connected to the line at the input to the half of the echo suppressor connected to the same line as the receiving ringer. This system would operate equally as well if this relay contact were connected to the line at the input to the half of the echo suppressor connected to the other line. Accordingly, while the invention has been disclosed as embodied in certain specific arrangements which are deemed 10 desirable, it is understood that it is capable of embodiment in many and other widely varied forms without departing from the spirit of the invention as defined by the appended claims.

What is claimed is:

20 1. In association with a transmission circuit, a transmission control system including an echo suppressor, means independent of the principal transmission over the circuit for applying thereto alternating current of certain frequencies, 25 signal receiving circuit responsive to said certain frequencies and connected to said transmission circuit and to said echo suppressor, and switching means controlled thereby for disabling said echo suppressor by the operation of said 30 signal receiving circuits.

2. In a transmission system, two one-way line sections for transmission in opposite directions, controlling means responsive to all currents in one of said line sections, switching means controlled thereby for disabling the opposite line section, means independent of the principal transmission over the system for applying to said first-mentioned line section alternating current of certain frequencies, a second controlling means associated with said disabled line section and responsive to currents of said certain frequencies, and switching means controlled thereby for permitting said currents of certain frequencies to be transmitted over said last-mentioned line section.

3. In a signaling system, two one-way line sections for transmission in opposite directions, a first controlling means responsive to all currents in one of said line sections, switching means controlled thereby for disabling the opposite line section, means independent of the principal transmission over the system for applying to said first-mentioned line section alternating current of certain frequencies, a second controlling means associated with the first-mentioned line section and responsive to said currents of said certain frequencies, and switching means controlled thereby for preventing said first controlling means from disabling the opposite line section.

4. In a transmission system, two one-way line sections for transmission in opposite directions, controlling means responsive to all currents in one of said line sections, switching means controlled thereby for disabling the opposite line section, means independent of the principal transmission over the system for applying to said first-mentioned line section an alternating current signal of arbitrarily chosen frequency, a second controlling means associated with said disabled line section and responsive to said alternating current signal, and switching means controlled thereby for permitting said signal to be transmitted over said last-mentioned line section.

5. In a transmission system, two one-way line sections for transmission in opposite directions, a first controlling means responsive to all currents in one of said line sections, switching means controlled thereby for disabling the opposite line section, means independent of the principal transmission over the system for applying to said first-mentioned line section an alternating current signal of arbitrarily chosen frequencies, a second controlling means associated with said first-mentioned line section and responsive to said alternating current signal, and switching means controlled thereby for preventing said first controlling means from disabling the opposite line section. 10

6. In a transmission system, a one-way line section for transmission from A to B and another line section for transmission from B to A, a first controlling means associated with both line sections and responsive to all currents, switching means controlled thereby for disabling the line from A to B when transmission is over the line from B to A, and for disabling the line from B to A when transmission is over the line from A to B, means independent of the principal transmission over the system for sending over either of said line sections an alternating current signal of arbitrarily chosen frequencies, a second controlling means associated with both line sections and responsive to said alternating current signals, and switching means controlled thereby for disconnecting the first controlling means from the line transmitting from A to B when said signals are transmitted in this direction, and from the line transmitting from B to A when said signals are applied to this line. 15 20 25 30 35

7. In a transmission system, a one-way line section for transmission from A to B and another line section for transmission from B to A, a first controlling means associated with both line sections and responsive to all currents, switching means controlled thereby for disabling the line from A to B when transmission is over the line from B to A, and for disabling the line from B to A when transmission is over the line from A to B, means independent of the principal transmission over the system for sending over either of said line sections an alternating current signal of arbitrarily chosen frequencies, a second controlling means associated with both line sections and responsive to said alternating current signals, and switching means controlled thereby for disconnecting the first controlling means from the line transmitting from A to B when said signals are transmitted over said line, 40 45 50 55 and from the line transmitting from B to A when said signals are applied to said line, said switching means controlled by said second controlling means being adapted to prevent the disabling of the line from B to A in response to energy in the line from A to B or to remove such disability if it has already been applied. 60

8. In a transmission system, a one-way line section for transmission from A to B, and another line section for transmission from B to A, a first controlling means associated with both line sections and responsive to all currents, switching means controlled thereby for disabling the line from A to B when transmission is over the line from B to A, and for disabling the line from B to A when transmission is over the line from A to B, a second controlling means responsive to certain signals and a switching means controlled by said first controlling means for connecting said second controlling means to the 65 70 75

line from A to B when transmission is over the line from B to A, and to the line from B to A when transmission is over the line from A to B, and switching means controlled by said second controlling means for disconnecting said first-mentioned controlling means from the line transmitting from A to B when said signals are transmitted in this direction, and from the line transmitting from B to A when said signals are applied to this line.

9. In a transmission system, a one-way line section for transmission from A to B and another line section for transmission from B to A, a first controlling means associated with both line sections and responsive to all currents, switching means controlled thereby for disabling the line from A to B when transmission is over the line from B to A and for disabling the line from B to A when transmission is over the line from A to B, means independent of the principal

transmission over the system for sending over either of said line sections an alternating current signal of arbitrarily chosen frequencies, a second controlling means associated with both line sections and responsive to said alternating current signal, and switching means controlled thereby for disconnecting the first controlling means from the line transmitting from A to B when said signals are transmitted over said line and from the line transmitting from B to A when said signals are applied to said line, said switching means controlled by said second controlling means being adapted to prevent the disabling of the line from B to A in response to the energy in the line from A to B or to remove such disability if it has already been applied, and similarly adapted to prevent or remove the disability of the line from A to B in response to energy in the line from B to A.

ELLIOT M. STAPLES. 20
